(57) **CLAIM**

The ornamental design for a beverage dispenser spout, as shown and described.

DESCRIPTION

FIG. 1 is a top, rear, left side perspective view of a beverage dispenser spout showing our new design;

FIG. 2 is a top plan view thereof;

FIG. 3 is a rear elevation view thereof;

FIG. 4 is a left side elevation view thereof;

FIG. 5 is a front elevation view thereof;

FIG. 6 is a right side elevation view thereof;

FIG. 7 is a bottom plan view thereof; and,

FIG. 8 is a top, front, right side perspective view thereof. The broken lines represent portions of the beverage dispenser spout that form no part of the claimed design.
